UNITED STATES PATENT OFFICE.

FRANK SUBRY, OF DENVER, COLORADO.

PUMP.

1,223,122.

Specification of Letters Patent. Patented Apr. 17, 1917.

Application filed May 29, 1916. Serial No. 100,451.

To all whom it may concern:

Be it known that I, FRANK SUBRY, a subject of the King of Italy, residing in the city and county of Denver and State of Colorado, have invented certain new and useful Improvements in Pumps; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in pumps of the double action or continuous flow type, and my object is to present an apparatus of this character comprising a very small number of working parts, and one that is most efficient in operation.

In carrying out my idea I employ a cylinder provided with intake and discharge ports diametrically opposed to each other, and a piston located within the said cylinder, the piston being composed of two parts, each part having a pair of grooves formed in its periphery, the grooves in one of said parts adapted to alternately communicate with the intake port, while the grooves in the other part alternately communicate with the discharge port as the piston is raised and lowered.

I also mount a cage upon the top of the cylinder, said cage being provided with cam surfaces which are engaged as the piston reciprocates by anti-frictional rollers carried by the piston stem, whereby the aforesaid operation is accomplished.

Having briefly outlined my improved construction, I will proceed to describe the same in detail, reference being made to the accompanying drawing, in which is illustrated an embodiment thereof. In this drawing,—

Figure 1 is a view in elevation of my improved construction.

Fig. 2 is a section taken on the line 2—2, Fig. 1, looking in the direction of the arrow.

Fig. 3 is a cross section taken on the line 3—4, Fig. 1, showing one position of the piston.

Fig. 4 is a cross section also taken on the line 3—4, Fig. 1, showing another position of the piston.

Fig. 5 is a vertical section of the piston taken on the line 5—5, Fig. 6.

Fig. 6 is a cross section of the piston taken on the line 6—6, Fig. 5.

Fig. 7 is a central vertical section taken on the line 7—7, Fig. 3, showing the piston in its lowermost position.

Fig. 8 is a central vertical section taken on the line 8—8, Fig. 4, showing the piston in its uppermost position.

Fig. 9 is a detail view of the piston and lower extremity of the piston stem, with parts separated to show the construction.

Fig. 10 is a detail view of the piston in elevation, showing the grooves which communicate with the discharge port of the cylinder.

Fig. 11 is a view similar to Fig. 10, showing the piston grooves which communicate with the intake port of the cylinder.

The same reference characters indicate the same parts in all the views.

Let the numeral 5 designate a pump cylinder provided with laterally disposed flanges 6 for securing the same in position. The cylinder casing has an intake opening 7 and a discharge opening 8 formed therein, and diametrically opposed to each other, the intake opening 7 adapted to register with a pipe 9 and the discharge opening 8 with a pipe 10, the said pipes being connected with a casing as disclosed at 12.

Within the cylinder is located a piston 13 composed of two parts 14 and 15 which are fitted together, the part 14 being recessed as shown at 16 to receive an offset portion 17 of the part 15. A piston stem 18 is secured in the upper extremity of the piston between the two parts of the latter by means of a rectangular-shaped part 19 secured to its lower extremity and projecting laterally beyond the stem, the said part 19 adapted to fit within a recess 20 of counterpart shape formed in the part 14 of the piston, and bear upon the upper surface of the offset portion 17 of the other part 15 of the said piston, the stem 18 projecting through an opening 21 formed in the upper extremity of said part 14 and which leads into the recess 20. The two parts 14 and 15 of the piston 13 are continually held in close engagement with the wall of the casing by means of springs 22 located in recesses 23 formed in

the portion 17 of the part 15, one extremity of said springs adapted to bear against the inner end of the recess 16 of the part 14.

Grooves A and B are formed in the periphery of the part 14, and the periphery of the part 15 is provided with grooves C and D, the grooves A and B adapted to alternately communicate with the intake opening 7, and the grooves C and D adapted to alternately communicate with the discharge opening 8. The groove A extends from the lower end of the piston to a point near the upper extremity of the latter, while the groove B extends from the upper end of the said piston to a point near its lower extremity, the said grooves being arranged in parallel relation (see Fig. 11). Also the groove C extends from the upper end of the piston to a point near the lower end of the latter, the lower extremity of the said groove being curved toward the groove D which extends from the lower end of the said piston to a point near its upper end, the upper extremity of this groove being curved toward the groove C. These grooves are also disposed parallel to each other (see Fig. 10).

A cage 24 is mounted upon the cylinder head by means of bolts 25 and the piston stem 18 is adapted to project through and above said cage, a packing 26 and a packing nut 27 being employed to form a water tight joint around the said stem where it passes through the cylinder head.

A pin 28 is mounted in the piston stem 18, the extremities of said pin being equipped with anti-frictional rollers 29 adapted to engage the walls 30 of openings 31 formed in the cage 24, the upper and lower walls of said openings being inclined as shown at 32 and 33 respectively, whereby they perform the function of cams when engaged by the rollers 29.

In view of the above description it is believed that the use and operation of my improved construction will be readily understood. Assuming that the piston is in the position disclosed in Figs. 3 and 7, this being its lowermost limit of movement, the groove A will be in communication with the intake opening 7 and the lower portion of the cylinder chamber, and the groove C will communicate with the discharge opening 8 and the upper portion of the said cylinder chamber. Now, as the piston travels upwardly fluid will be drawn into the lower portion of the cylinder from the pipe 9 through the intake opening 7 and the groove A, and, at the same time the fluid in the upper portion of the said cylinder will be forced out of the latter through the groove C, the discharge opening 8 and the pipe 10.

Before the piston 13 reaches its upward limit of movement, the anti-frictional rollers 29 carried by the piston stem 18, will engage

the lower end of the upper inclined wall portions 32, and, as the piston further ascends, the rollers will ride upwardly and laterally upon these said portions 32 until they reach the upper extremities of the latter, whereby the piston will be rotated to the position disclosed in Figs. 4 and 8. When the piston is in this position, the groove A is cut off from the intake opening 7 and the groove B placed in communication therewith, and the groove C is cut off from the discharge opening 8 and the groove D placed in communication with the same. The portion of the cylinder above the piston is now in communication with the intake opening 7 and the portion below the piston is in communication with the discharge opening 8, whereby, as the said piston descends, fluid is drawn into the upper portion of the cylinder through the pipe 9, intake opening 7 and the groove B, and, at the same time the fluid in the lower portion of the cylinder is being discharged through the groove D, discharge opening 8 and the pipe 10.

Before the piston reaches its lowermost limit of movement, the anti-frictional rollers 29 will engage the upper ends of the lower inclined wall portions 33, and as the piston further descends, these rollers will ride downwardly and laterally upon the said wall portions until they reach the lower extremities of the latter, thereby rotating the piston back to the position disclosed in Fig. 7, this position being its lowermost limit of movement.

It should be noted that the upper and lower extremities of the grooves D and C respectively, are curved, whereby one of the said grooves or both are continually in communication with the discharge opening 8.

Having thus described my invention, what I claim is,

1. In a pump, the combination of a cylinder provided with intake and discharge ports, a piston located in said cylinder and having two sets of grooves formed therein, one groove of each set extending from the bottom of the piston to a point near its upper extremity, while the other groove extends from the top of the piston to a point near its lower extremity, and the upper extremity of one groove and the lower extremity of the other groove of one of said sets being curved toward the adjacent groove, and means for rotating the piston during its reciprocation, for the purpose set forth.

2. In a pump, the combination of a cylinder, a piston located in the said cylinder and having grooves formed in its periphery, a member mounted upon top of the cylinder provided with open spaces in its opposite sides, the upper and lower walls of said openings being respectively inclined in reverse directions, and means carried by the

stem of the piston adapted to engage said inclined walls during the reciprocation of the said piston for rotating the latter.

3. In a pump, the combination of a cylinder, a piston located in the said cylinder and having grooves formed in its periphery, a member mounted upon top of the cylinder provided with openings in its opposite sides, the upper and lower walls of said openings being inclined, a pin carried by the stem of the piston, and rollers mounted upon the op-

posite extremities of said pin adapted to engage the said inclined walls during the reciprocation of the piston, for the purpose set forth.

15

In testimony whereof I affix my signature, in presence of two witnesses.

FRANK SUBRY.
